UNITED STATES PATENT OFFICE.

VIRGIL T. GRABS, OF KING, NORTH CAROLINA.

SECTIONAL KNOCKDOWN FLUE.

Application filed December 7, 1925. Serial No. 73,732.

This invention relates to sectional knock-down flues.

The object is to provide a flue of strong and light construction, especially adapted for conducting heat and distributing the same in tobacco barns for the purpose of curing tobacco, the said flue being constructed of a continuous series of sections formed of normally flat, rectangular pieces of suitable sheet metal adapted to be bent into tubular form at the place where used, said tubular sections being rigidly held together, in end to end relation by temporary fastening means, to form a substantially leak-proof flue of the desired length, and being adapted to be quickly and easily taken apart and packed into compact form to be readily loaded and transported to another scene of action, with the metal sheets comprising the tubular sections in their normal, flat condition, so as to occupy a minimum amount of space in moving same.

Another object is to provide a sectional flue of this character wherein the sheets constituting the tubular sections are effectually prevented from expanding or collapsing, the free edges of the same, forming the longitudinal seams of the sections, being engaged by detachable longitudinal members that prevent such action, and also prevent the escape of the heat through such seams, while the abutting ends of the several sections are also rigidly clamped together by transverse members surrounding the joints, the latter members and the longitudinal members being in staggered relation to each other to provide a strong and rigid structure.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:—

Figure 1 is a side elevation of a portion

of a flue constructed in accordance with this invention.

Figure 2 is a transverse sectional view through the same.

Figure 3 is a detail longitudinal, sectional view.

Figure 4 is a detail perspective view of a portion of one of the longitudinal seam engaging strips.

Referring to the drawing there is shown a flue composed of tubular sections 1 of sheet metal having a normal tendency to straighten out into substantially flat condition when released, each sheet being of rectangular form of the desired dimensions and adapted to be shipped or transported in such flat condition and arranged in piles so that the same may occupy small space on a truck, car or wagon. The sheets are adapted to be bent into tubular form by hand, at the scene of operations, and the free, longitudinal edges 2 thereof are arranged in overlapping relation to each other, as shown in Figure 2 of the drawing.

The tubes are placed with their ends 3 in abutting relation, while being held in said cylindrical form, and a strip 4, having oppositely disposed seats 5 formed therein is engaged with the aligned longitudinal edges 2 of the abutting tubes. Each strip is applied to two abutting tubes, the said strips being of substantially the same length as the tubes, and the center of the strip is located substantially at the joint between two adjacent sections, so that when adjoining sections are arranged in line, in abutting relation and the coating strip or strips are applied, it will be seen that a continuous series of strips result, with their joints staggered with the joints of the tubes.

Coupling bands 6 completely encircle the flue line at the joints between the tubular sections, said bands being formed of strips of suitable metal of a width to extend partially along each abutting end, so as to effectually cover the joint and prevent escape of the heat, and at the same time exert sufficient clamping action, when tightened, to rigidly hold the several sections together as a continuous flue.

In order to exert such clamping action, the length of the clamping bands is such as to completely encircle the tubes, with the ends adjacent to the aforesaid strips so as to permit of a slight circumferential bind.

ing movement of the same, and at one end of the band there is attached an upstanding ear 7 having a suitable aperture 8 for the reception of a threaded bolt 9 which has an integral foot portion 10, adapted to be riveted or otherwise secured to the other end of the band, the said foot being so shaped as to space the bolt away from the band sufficiently to pass over the interposed strip 4 and traverse the ear 7. The terminal of the bolt is drawn through by a nut 11 thus causing the band to hug the sections and bind the same together.

The aforesaid strips 4 are formed of sheet metal of a width to permit the marginal portion on one side to be bent over towards the central body portion on one side of and in spaced relation to the latter, while the other side marginal portion is likewise turned back, at the other side of the body portion, as clearly shown in Figure 4 of the drawing, to form the seats 5, as stated.

From the foregoing it will be seen that a simple, strong and durable structure has been provided for conducting heat or the like, and that by arranging the strips and the bands in the manner described, the flue may be easily set up or taken down for storage or transportation, the flat sheets occupying a minimum amount of space and safeguarded from damage by denting or bending, whereas the rigid sectional tubes, where they are not collapsible, are easily injured or rendered unfit for use and, by reason of their bulk, are not easily carried in quantities.

What is claimed is:—

1. A heat-conducting pipe composed of tubular sections formed of flat sheets bent and temporarily held in tubular form, the side edges of said sheets overlapping each other

and said sections being placed in end-to-end relation to each other with their overlapped edges in alinement, circular bands surrounding the sections and overlapping their abutting ends, the ends of the bands being spaced apart at the overlapped edges of the sections and provided with means for drawing the ends together, and bent sheet metal strips having opposite seats for engaging the overlapped edges of each section, said strips abutting at their ends at points midway between the joints of the several sections and the gaps between the ends of said bands being wider than said strips.

2. A tobacco-curing flue formed of similar, abutting, sheet metal sections, each composed of a normally flat sheet held temporarily in tubular form with the side edges overlapped, coupling bands surrounding the sections, the ends of the bands being located adjacent to the said overlapped edges, an outstanding, apertured ear carried by one of said ends, a screw carried by the other end to traverse the ear, a nut for binding the band around the joint, a strip equal in length to each pipe section, said strip being formed of sheet metal and bent longitudinally to cause each marginal edge thereof to extend parallel on either side of and in spaced relation to the center portion of the strip to provide opposed seats for the overlapped edges of the sections and to pass between the ends of the band, bridging the joint and abutting with the next adjacent strips at each end substantially at the centers of each section.

In testimony that I claim the foregoing as my own, I have hereto affixed my signature.

VIRGIL T. GRABS.
